(57) **CLAIM**

We claim the ornamental design for a cellular fabric with triangular cells, as shown and described.

DESCRIPTION

FIG. 1 is a front isometric view of the fabric of the present invention with cells shaped like equilateral triangles in an open condition.

FIG. 2 is an enlarged front isometric view similar to FIG. 1. FIG. 3 is a left side elevation view of the fabric as shown in FIG. 2 with the right side elevation view being a mirror image. FIG. 4 is a front elevation view of the fabric as shown in FIG. 2.

FIG. 5 is a top plan view of the fabric as shown in FIG. 2 with the bottom plan being identical.

FIG. 6 is a rear elevation view of the fabric as shown in FIG. 2.

FIG. 7 is a front isometric view of the fabric as shown in FIG. 2 with the cells in a closed condition.

FIG. 8 is a left side elevation view of the fabric as shown in FIG. 7 with the right side elevation being a mirror image.

FIG. 9 is a front elevation view of the fabric as shown in FIG. 7.

FIG. 10 is a top plan view of the fabric as shown in FIG. 7.

FIG. 11 is a bottom plan view of the fabric as shown in FIG. 7; and,

FIG. 12 is a rear elevation view of the fabric as shown in FIG. 7.
